(57) CLAIM

The ornamental design for a wireless communications headset, as shown and described.

DESCRIPTION

This application is related to U.S. design application Ser. No. 29/265,057 and 29/265,061 filed concurrently herewith.

FIG. 1 is an upper left front perspective view of a wireless communications headset showing our new design;

FIG. 2 is an upper right front perspective view thereof;

FIG. 3 is an top end view thereof;

FIG. 4 is a bottom end view thereof;

FIG. 5 is a front side elevation view thereof;

FIG. 6 is a rear side elevation view thereof;

FIG. 7 is a left side elevation view thereof; and,

FIG. 8 is a right side elevation view thereof.
